UNITED STATES PATENT OFFICE

150,573

DESIGN FOR A PICTURE VIEWER

Frederick B. Ingram, Rock Island, Ill.

Application April 26, 1947, Serial No. 138,640

Term of patent 7 years

(Cl. D57—1)

To all whom it may concern:

Be it known that I, Frederick B. Ingram, a citizen of the United States, and a resident of Rock Island, in the county of Rock Island and State of Illinois, have invented a new, original, and ornamental Design for a Picture Viewer, of which the following is a specification, reference being had to the accompanying drawing, forming a part thereof, and in which:

Fig. 1 is a front perspective view of a picture viewer showing my new design;

Fig. 2 is a bottom plan view;

Fig. 3 is a rear elevational view thereof.

I claim:

The ornamental design for a picture viewer, as shown.

FREDERICK B. INGRAM.
